UNITED STATES PATENT OFFICE

STEPHEN L. YOUNG, OF SYRACUSE, NEW YORK

SPRING-LEAF WRAPPER

Application filed November 11, 1924. Serial No. 749,159.

This invention relates to wrappers for leaf springs, as the springs of motor vehicles, and has for its object a wrapper which is particularly simple and economical in construction, 5 readily applied to the leaf spring, and which is grease or oil tight, and can withstand the pressure without leaking, of grease guns or other pressure devices employed to inject grease or oil into the various bearings of a motor vehicle.

10 The invention consists in the novel features and in the combinations and constructions hereinafter set forth and claimed.

In describing this invention reference is 15 had to the accompanying drawings in which like characters designate corresponding parts in all the views.

Figure 1 is a fragmentary side elevation of a spring provided with my wrapper, the contiguous portion of the frame of the vehicle 20 and the axle being also shown.

Figure 2 is an enlarged fragmentary elevation of the leaf adjacent a spring clip, the wrapper being shown in section.

25 Figure 3 is a sectional view on line 3—3, Fig. 1.

Figure 4 is a sectional view on line 4—4, Fig. 2.

Figure 5 is a fragmentary plan view of the 30 base strip.

Figure 6 is a side elevation of parts seen in Fig. 5.

Figure 7 is a fragmentary detail view of the 35 portion of the wrapper adjacent a spring clip.

Figures 8 and 9 are respectively enlarged detail views of the joint at the lower right hand corner of Figure 3.

This leaf spring wrapper comprises, generally, a base strip arranged to extend lengthwise of the spring and usually lengthwise of the under face of the lower or main leaf of the spring, a wrapper of flexible or fibrous material secured at its edges with the opposite 40 edges of the base strip, the base strip having means for coacting with the wrapper for securing the wrapper to the base strip.

45 1 designates the base strip, which preferably extends lengthwise of the lower side of the spring 2, this base strip preferably having

upstanding lugs or flanges 3 struck therefrom and lapping the opposite sides of the springs of the lower leaf to hold the base strip from lateral displacement, especially while the flexible wrapper is being stretched and applied. 55 The base strips are furnished in certain standard lengths, which can be cut off to suit the length of the spring and the distance from the end of the spring to the axle 4. The spring here shown is of the semi-elliptical type pivoted at one end at 5 to the sill 6 of the vehicle, and secured intermediate of its ends to the axle.

50 8 is the wrapper of flexible or fibrous material, as leather or one of the fibrous products usually in the nature of imitation leather as pantasote, the wrapper being secured at its opposite edges to the base strip, and the base strip being provided with means by which the wrapper when wrapped around the spring 60 can be tightened and secured to the base strip, such means being movable into its final position and when so moved tending to additionally tighten the wrapper.

55 As here illustrated the base strip 1 is provided with similar means on opposite edges thereof and the wrapper 8 may be first secured to one edge before being wrapped around the spring and secured to the other edge of the base strip or both margins of the 65 wrapper may be attached to the base strip after it is applied to the spring. The means for attaching the wrapper 8 to the base strip as here shown comprises down turned flanges 70 9 on opposite edges of the base strip and prongs 10 on the lower ends of the flanges, these flanges being here shown as alternating with upwardly extending flanges and lugs 3. The fabric 8 or the opposite margins thereof are hooked on the prongs 10. These 75 prongs are here shown as extending outwardly at an angle to the flange 9.

80 The fabric or wrapper 8 is first hooked over the prongs 10 along one edge of the base strip as seen at the left hand side of 85 Figures 3 and 4, then these prongs 10 are clenched by being folded around and clenched onto the inner face of the flange 9, and the flange 9 folded on the lower face of the strip 90 to form a joint in the nature of a lock seam 100.

or rolled joint. The wrapper is then stretched around the spring and hooked in the prongs 10 at the other side of the base strip, and then these prongs 10 and the flange 9 are folded, rolled or clenched as before. The folding or rolling finally tightens the fabric onto the spring.

When the spring is provided with spring clips and the spring clips are not removed 10 for the purpose of applying the wrapper, although the base strip may extend the length of the spring and under the spring clip as shown at 12, the fabric wrapper 8 may be formed in sections terminating at the spring 15 clip; and in order to form a tight joint over the spring clip, an additional wrapper 13 is lapped over the ends of the former wrapper 8. The margins of the wrapper 13 are secured to the same lugs or prongs 10 that the contiguous 20 part of the wrapper 8 is secured to. Or the wrapper 8, instead of being formed in sections may be formed with a slit as 14 of the shape shown in Fig. 7, through which the ends 15 of the bolt 16 of the clip 12 extend, and the outer wrapper 13 covers these 25 projecting ends 15 and the bolt 16.

Oftentimes an oiler is used provided with a coupling to receive the nozzle of a grease gun. In such cases the wrappers 8 and 13 30 are arranged relative to the oiler, practically the same illustration is used in connection with the spring clip with the exception that the nozzle or receptacle of the oiler extends through the wrappers so the nozzle of a grease gun can be attached thereto.

This spring leaf wrapper is particularly advantageous in that it consists of a long single base strip to which the wrapper proper is applied, and can be readily applied by an unskilled workman and without the use of special tools, a pair of pliers and possibly a hammer being all that is necessary.

What I claim is:—

1. A cover for leaf springs comprising a 45 base strip arranged to extend lengthwise of the spring and to lie directly against the spring and a wrapper of foldable material secured at one side margin to one margin of the base strip and foldable around the spring, the base strip having means along its other margin for hooking the wrapper thereon, the base strip forming an anchor for the wrapper while being wrapped and stretched around the spring before being hooked onto the base strip.

2. A cover for leaf springs, comprising a base strip arranged to extend lengthwise of the spring, and a wrapper of foldable material secured at one side margin to one margin of the base strip, and foldable around the spring, and the base strip having at its other margin means for securing the wrapper thereto, the last mentioned means, comprising 60 prongs on which the margin of the wrapper

is hooked, said prongs being foldable back onto the strip.

3. A cover for leaf springs, comprising a base strip arranged to extend lengthwise of the spring, and a wrapper of foldable material secured at one side margin to one margin of the base strip, and foldable around the spring, and the base strip having at its other margin means for securing the wrapper thereto, the last mentioned means comprising 70 downwardly extending flanges terminating in prongs on which the wrapper is hooked, the flanges being foldable back onto the base strip.

4. A cover for leaf springs, comprising a 80 base strip arranged to extend lengthwise of the spring, and a wrapper of foldable material secured at one side margin to one margin of the base strip, and foldable around the spring, and the base strip having at its other margin means for securing the wrapper thereto, the last mentioned means comprising 85 downwardly extending flanges terminating in prongs on which the wrapper is hooked, the prongs being foldable backwardly onto 90 the flanges, and the flanges being foldable onto the base strip.

5. A cover for leaf springs, comprising a base strip arranged to extend lengthwise of the spring, the base strip having means at 95 its margin forlapping the sides of the spring, and a wrapper of foldable material secured at one side margin to one margin of the base strip, and foldable around the spring, and the base strip having at its other margin 100 means for securing the wrapper thereto, the last mentioned means comprising downwardly extending flanges having outwardly extending prongs on which the wrapper is hooked, the prongs being foldable inwardly 105 toward the center of the base strip onto the inner side of the flange, and the flange being foldable inwardly onto the base strip.

6. A cover for leaf springs comprising a base strip arranged to extend lengthwise of 110 the spring and extending substantially the width of the spring and a wrapper of foldable material, the base strip having means along its margins located at the corners of the spring for connecting the wrapper 115 thereto.

7. A cover for leaf springs comprising a base strip arranged to extend lengthwise of the spring and extending substantially the width of the spring and a wrapper of foldable material, the base strip having prongs at 120 its margins located at the corners of the spring for connecting the edges of the wrapper thereto.

8. A cover for leaf springs comprising a 125 base strip and a wrapper of flexible material, the strip being constructed to extend lengthwise and substantially the full width of the spring, the strip having means located substantially at the corners of the spring for 130

securing the wrapper thereto and said wrapper being securable first to the means at one corner of the strip and then wrappable tightly around the spring and then securable to the 5 means on the base strip at the other corner of the spring, all whereby the wrapper can be pulled tightly around the spring and conform to the taper thereof.

In testimony whereof, I have hereunto 10 signed my name at Syracuse, in the county of Onondaga and State of New York, this 1st day of November, 1924.

STEPHEN L. YOUNG.
